Patented Mar. 26, 1929.

UNITED STATES PATENT OFFICE.

HARRY E. PFAFF, OF WARREN, OHIO, ASSIGNOR TO ALEX METHERELL, OF HAMILTON, CANADA.

CHAIN WRENCH.

Application filed December 23, 1927. Serial No. 242,162.

This invention relates to a chain wrench for gripping round articles such as pipes, flanges, bolts, and the like.

Chain wrenches have previously been constructed so that the gripping action of the wrench increases with increase in the leverage brought to bear by it upon the article gripped.

The object of the invention is to provide a chain wrench having this characteristic, which is adapted to grip articles of various sizes, and to engage an article of small diameter as firmly as an article of relatively great diameter.

A further object of the invention is to provide a chain wrench in which the locking action of the wrench during its use is wholly automatic, and which avoids the use of springs or operating levers in order to secure a locked engagement of the gripping chain of the wrench when leverage is brought to bear upon an article to be gripped.

In the accompanying drawings Figure I is a side elevation of the chain wrench of the present invention, showing the chain thrown around a section of pipe, and the handle in the position to receive the chain; Figure II is a side elevation, showing the position of the parts after the chain is positioned and locked by moving the handle downward; Figure III is a side elevation of the wrench illustrating its position inverted for counter rotation; Figure IV is a fragmentary side elevation illustrating the engagement of the chain of the wrench with an article of relatively small diameter; and Figure V is a plan view of the wrench, illustrating the relative positioning of the parts, and showing the engagement of the wrench with a flange of relatively slight width.

In the drawings the reference numeral 1 designates the handle member of the wrench, which is bifurcated adjacent its forward extremity to provide a yoke 2 embracing the gripping jaw 3 of the wrench, and providing a mounting space for the chain locking means thereof.

The gripping jaw 3 of the wrench is pivotally mounted in the yoke 2 by means of a pivot pin 4 passing through the yoke and jaw, and has a roughened, or serrated, forward gripping face 5 formed on an arc to engage the surface of a circular object, such as a pipe. The chain 6 of the wrench, which

is of the usual type comprising center links 7 and side links 8, is attached in the seat 9 of the jaw 3 by means of a pin 10.

The rearward face 11 within the yoke 2 is irregularly curved to provide a curved extension 12 and an indentation 13 for engaging the chain 6 to lock the same in gripping position. A dog 14 is eccentrically pivoted on a pin 15, which is mounted in the yoke 2 to one side of the longitudinal center line thereof. The face 16 of the dog which cooperates with the chain 6 is curved to provide extensions 17 and 18, which cooperate with the face 11 to engage the chain in locked position.

With particular reference to Figure I of the drawings the chain 6 has been passed around a pipe A, and the contacting face 5 of the jaw 3 brought into contact with the periphery of the pipe. The free end of the chain 6 is then drawn through the space in the yoke 2 which lies to the rear of dog 14. During this action the dog 14 oscillates freely and permits the insertion of the chain.

Figure II of the drawings illustrates the locking of the chain 6. In this position it will be noted that the handle 1 of the wrench has been lowered from its position as shown in Figure I, while the position of the jaw 3 of the wrench remains substantially unchanged. This action produces a tendency for the edge 17 of the dog 14 to swing outwardly, causing the edge 18 to bear rearwardly on the chain, and to force it into locking engagement with the protuberance 12 and indentation 13 of the face 11. During this action the chain 6 is forced through the yoke 2 of the wrench a greater distance than it may be drawn by hand.

It will be further noted that the line from the center of the pivot pin 15 of the dog, as shown in dotted line 'a' is longer than the line between the center of the pivot pin and the pin of the edge or extension 18, as shown by the dotted line 'b'. This gives a greater effective lever arm for rotating the edge 18 inwardly, than for the reverse of this action. After the chain is locked, in the position of the parts shown in Figure II of the drawings, further rotation of the handle member 1 serves to still further tighten this locking engagement, which is not broken until the handle is rotated in a counter direction. Fig-

ure III shows the wrench locked around the pipe A for rotation counter to that shown in Figure II.

It is thus seen that the locking of the chain is wholly automatic, taking place merely by means of the same turning movement which is desired for rotating the article gripped by the wrench. The extension 19 on the dog 14 is for the purpose of loosening the locking engagement if the parts should become jammed during violent use of the wrench, and it also serves to keep the dog 14 balanced in the position shown in Fig. I while the chain is being passed through yoke 2.

Figure IV of the drawings illustrates the gripping of a circular object B of relatively small diameter. This object is engaged, similarly to the object A of relatively great diameter, between the gripping face 5 of the jaw 3 and the chain 6. In order that the chain 6 may be brought sufficiently close to the face 5 of the jaw, the jaw is slotted inwardly from the ends of the face 5, as at 20, so that the chain may lie in these slots to closely engage the object B. After the chain has been locked in the body of the wrench, the slight swivelling movement of the jaw produced by further rotation of the handle produces a tendency toward a tighter gripping of the object B.

What I claim is:

1. A chain wrench comprising a handle member having a chain receiving passage with a chain engaging seat, a pivotally mounted jaw on said handle member, a gripping chain attached to said jaw, and an eccentrically pivoted locking member having a contacting face with two chain engaging points thereon arranged to coact with the chain engaging seat of the handle member.

2. A chain wrench comprising a handle member having a chain receiving passage with a chain engaging seat, a pivotally mounted jaw on said handle member, a gripping chain attached to said jaw, and a locking member eccentrically pivoted in the chain receiving passage of the handle member and having two chain engaging points so arranged with respect to the to the pivotal center of the locking member and the chain engaging seat of the handle member that they automatically lock the chain upon movement of the handle member when the chain embraces an object to be gripped.

3. A chain wrench comprising a handle member having a chain receiving passage with a chain engaging seat, a protuberance on said seat, a pivotally mounted jaw on said handle member, a gripping chain attached to said jaw, a locking member pivotally mounted in the chain receiving passage, a protuberance on said locking member arranged to coact with the protuberance on the seat of the handle member to grip the chain, and a

point on the locking member arranged to engage the chain to cause movement of the member for producing such gripping action upon movement of the handle member when the chain embraces an object to be gripped.

4. A chain wrench comprising a handle member having a chain receiving passage with a chain engaging seat, a protuberance on said seat, a pivotally mounted jaw on said handle member, a gripping chain attached to said jaw, a locking member pivotally mounted in the chain receiving passage, a protuberance on said locking member arranged to coact with the protuberance on the seat of the handle member to grip the chain, and a point on the locking member arranged to engage the chain to cause movement of the member for producing such gripping action upon movement of the handle member when the chain embraces an object to be gripped, the distance from the pivotal center of the locking member to the gripping protuberance being less than the distance from the pivotal center of the locking member to the actuating point thereon.

5. A chain wrench comprising a handle member having a chain receiving passage with a chain engaging seat, a pivotally mounted jaw on said handle member, a gripping chain attached to said jaw, said jaw having slots extending inwardly from the corners of the gripping face thereof to provide seats for the chain, and an eccentrically pivoted locking member having a contacting face with two chain engaging points thereon arranged to coact with the chain engaging seat of the handle member.

6. A chain wrench comprising a handle member having a chain receiving passage with a chain engaging seat, a pivotally mounted jaw on said handle member, a gripping chain attached to said jaw, said jaw having slots extending inwardly from the corners of the gripping face thereof to provide seats for the chain, and a locking member eccentrically pivoted in the chain receiving passage of the handle member and having two chain engaging points so arranged with respect to the pivotal center of the member and the chain engaging seat of the handle member that they automatically lock the chain upon movement of the handle member when the chain embraces an object to be gripped.

7. A chain wrench comprising a handle member having a chain receiving passage with a chain engaging seat, a protuberance on said seat, a pivotally mounted jaw on said handle member, a gripping chain attached to said jaw, said jaw having slots extending inwardly from the corners of the gripping face thereof to provide seats for the chain, a locking member pivotally mounted in the chain receiving passage, a protuberance on said locking member arranged to coact with the protuberance on the seat of the handle mem-

ber to grip the chain, and a point on the locking member arranged to engage the chain to cause movement of the member for producing such gripping action upon movement of the handle member when the chain embraces an object to be gripped.

8. A chain wrench comprising a handle member having a chain receiving passage with a chain engaging seat, a protuberance on 10 said seat, a pivotally mounted jaw on said handle member, a gripping chain attached to said jaw, said jaw having slots extending inwardly from the corners of the gripping face thereof to provide seats for the chain, a locking member pivotally mounted in the chain receiving passage, a protuberance on said

locking member arranged to coact with the protuberance on the seat of the handle member to grip the chain, and a point on the locking member arranged to engage the chain to cause movement of the member for producing such gripping action upon movement of the handle member when the chain embraces an object to be gripped, the distance from the pivotal center of the locking member to the gripping protuberance being less than the distance from the pivotal center of the locking member to the actuating point thereon.

In witness whereof, I hereunto set my hand.

HARRY E. PFAFF.
